UNITED STATES PATENT OFFICE.

ELIAS R. LOCKWOOD, OF PRATT, KANSAS.

TUBULAR WELL-PLUNGER.

No. 852,185.

Specification of Letters Patent.

Patented April 30, 1907.

Application filed May 4, 1906. Serial No. 315,152.

To all whom it may concern:

Be it known that I, ELIAS R. LOCKWOOD, a citizen of the United States, and a resident of Pratt, in the county of Pratt and State of Kansas, have invented a new and Improved 5 Tubular Well-Plunger, of which the following is a full, clear, and exact description.

This invention relates particularly to improvements in a device for holding the plunger valve open to permit water to pass through the plunger when it is withdrawn from the well tube, the object being to provide a device for this purpose, that will be simple in construction and that will positively hold the valve open.

I will describe a tubular well plunger embodying my invention, and then point out the novel features in the appended claims.

Reference is to be had to the accompanying drawings forming a part of this specification, in which similar characters of reference indicate corresponding parts in all the figures.

Figure 1 is a longitudinal section of a plunger showing a valve lifting and holding device embodying my invention; Fig. 2 is a perspective view of the lifting and holding device; and Fig. 3 is a section on the line 3—3 of Fig. 1.

The plunger comprises an upper section 5 and a lower section 6, which are secured together by screw-threads, in the usual manner; and attached to the plunger are leathers 7. The upper end of the tubular plunger member 6 forms a valve-seat for a puppet valve 9, and at the lower end of said member 6 there is an annular flange 10 provided with diametrically opposite notches 11 which forms guides for the valve lifting and holding devices consisting of a strip of resilient metal 35 having side members 12, 13 connected at the lower portion by a cross-member 14. The side members 12 and 13 which are movable within the member 6 of the plunger are provided with inward depressions 15, below 40 which are inward depressions 16.

When the pump is in operative condition the valve lifting and holding devices will be in the position indicated in full lines in Fig. 1; that is, it will be locked in its lower position by the walls of the depressions 15 engaging 50 over the upper and lower sides of the flange 10.

When it is desired to draw the plunger from the well tube it is first forced downward so that the lower portion of the lifting and holding device will engage with the bottom 55 of the well and force the said device into the plunger to engage with and lift the valve 9. At this time the walls of the depressions 16 will engage over the upper and lower sides of the flange 10, thus holding the valve open as 60 indicated by dotted lines in Fig. 1, permitting water that may be in the discharge tube to flow out.

Having thus described my invention I claim as new and desire to secure by Letters 65 Patent:

1. A tubular plunger, a valve therein, the lower portion of the plunger having an interior annular flange provided with opposite notches, and a valve lifting and holding device consisting of a length of resilient metal 70 slidable through said notches, and having upper depressions for engaging with the flange, and lower depressions for engaging with the flange.

2. A lifting and holding device for a well plunger valve, consisting of a strip of resilient metal having side members and a cross-member at the lower portion in said side members, each of said side members having two inward 75 depressions.

In testimony whereof I have signed my name to this specification in the presence of two subscribing witnesses.

ELIAS R. LOCKWOOD.
